(57) **CLAIM**

We claim, the ornamental design for a luminaire, as shown and described.

DESCRIPTION

FIG. 1 is a side view of a second embodiment of the invention, the luminaire being symmetric about a center axis; FIG. 2 is a top view of the embodiment of FIG. 1; FIG. 3 is a bottom view of the embodiment of FIG. 1; and, FIG. 4 is a first perspective view of the embodiment of FIG. 1. The dotted lines shown in FIGS. 1, 2, and 4 indicate that the outer diameter and shape of the lens represented by the dotted lines may have any size diameter and may be flat or curved. The dash-dot-dot lines shown between the heat sink portion and base portion in FIGS. 1, 3 and 4 indicate the heat sink portion may be of any length.

The phantom lines shown in FIGS. 1, 3 and 4 are environmental and not part of the claimed design.

The dash-dot lines shown in FIG. 1-4 indicate that the vent elements are environment and not part of the claimed design. The broken line showing of top and bottom of the bulb is included for the purpose of illustrating only and forms no part of the claimed design.
